UNITED STATES PATENT OFFICE.

HOMER ANDERSON, OF PEEKSKILL, NEW YORK.

SPARK-INDICATOR.

1,306,844.

Specification of Letters Patent. Patented June 17, 1919.

Application filed August 9, 1915. Serial No. 44,434.

To all whom it may concern:

Be it known that I, HOMER ANDERSON, a citizen of the United States, and resident of Peekskill, in the county of Westchester 5 and State of New York, have invented a certain new and useful Spark-Indicator, of which the following is a specification.

This invention relates to static current ignition systems in explosive engines, and 10 has for its object an indicator that will show the condition of the sparking at the spark plugs in the cylinders of the engines. It is applicable to any engine whether it be on an automobile, boat, or elsewhere; and it is 15 made in single and in multiple units, for use directly upon the spark plug or anywhere intermediate between the spark plug and the current distributor. Made in multiple units it is designed to be placed with- 20 in the vehicle where used, so that it will be directly in view of the driver of the machine. The objects are attained by the means set forth in this specification and the accompanying drawings, in both of which 25 like letters and numbers refer to similar parts throughout the several views.

Figure 1 is a plan of the top of the device shown in Fig. 2. Fig. 2 is a front elevation of the device as a single unit. Fig. 3 is a 30 vertical longitudinal section of the device. Fig. 4 is a plan partly in section of a multi-form embodying the equivalent of four units. Fig. 5 is an elevation of the device in multiple. Fig. 6 is a vertical transverse 35 section of a casing inclosing the device. Fig. 7 shows a spring method of securing the casing to the device. Fig. 8 is a plan of the bottom of the unit shown in Figs. 2 and 3. Fig. 9 is a plan of a development 40 of the units around a central point. Fig. 10 is an elevation partly in section of the central portion of the device shown in Fig. 9. Fig. 11 is a modified form of the device as a unit.

45 Figs. 1, 2, 3 and 11 show a device comprised of a base *a* of fiber, hard rubber, porcelain or other suitable non-conducting material, of rectangular, square, or circular outer contour. Centrally a recess *r* is cut 50 into the base somewhat past the center, and forward of the center of the base the material is cut away to make the recess of conical form, as in Figs. 2, 3, 4, 5 and 11, or it may be flared from the bottom of the chamber to the face, as in Figs. 1, 6, 9 and 10.

Around the outer edge of the conical re-

cess *l* a recess *m* is formed to receive a plate of glass, mica or other transparent material, as at *n*. A hole is made vertically through the base intersecting the recess, and threaded to receive through the top of the base a screw *b*, and through the base below the recess a screw *c*. The screw *b* is pointed upon its inner end, and is provided outside of the base with a check nut *e* and a thumb 60 nut *i*. The screw is slotted in its outer end for the use of a screw driver. The screw *c* is shown with a blunt inner point, a shoulder 11 to abut against the outer surface of the base, and the outer end of the screw is 65 elongated, turned at an angle to the base as at 12, and terminates in a flattened end *d*, perforated as at *d'*, Fig. 3.

This unit indicator can be used by attaching it by the arm *d* to the spark plug, and 70 the circuit wire under the nut *i*.

By making a number of these units in one base, as in Figs. 4 and 5 the device may be placed independently of the spark plugs, and at any point of observation where all 80 the sparkings may be seen at a glance. The regular form would be as shown in Fig. 4, with the lower screws *c'* provided with check nuts as at *f' g'*, the screws *b* being as in Fig. 5, and as shown in broken lines in 85 Fig. 6. Vertical sections through the centers of the sparking points in either Figs. 4 or 5 would show the same as in Fig. 3, except as to the terminals of the lower screws *c'*, which, in the multiple device, are 90 adapted for direct wire connections, as in Figs. 4 and 6.

The combination shown in Fig. 4 is designed for a four cylinder engine and is 95 adapted for placement on the dashboard of a vehicle, as in Fig. 6. A representing the dashboard, 3 the wires from the current distributor, 4 the wires leading to the four spark plugs. A casing *t'*, Figs. 4, 6 and 7, incloses the indicator. An opening *t''* discloses the recesses *l*, and a plate of glass is under the opening in the casing. To secure the casing on the base springs *v*, Figs. 4 and 7, are fast to the casing, and they catch in recesses *v'* in the ends of the base, 100 as in Figs. 6 and 7.

In cases where one side of a circuit can be connected with the electrodes on one side of the indicator and a distributor can take the current through the electrodes of the other 110 side of the indicator, the electrodes of the receiving side can be attached to a single plate,

as at *h*, Fig. 5, with a single wire connector *b' f g*. This form of indicator resolves itself into a circular form of construction as in Fig. 9. A heptagonal, or it may be round, 5 base is used for a four cylinder engine, the distributing connections are made upon four sides as shown, with the central electrode *8 8'* attached to the fifth side. This central electrode is shown in elevation in Fig. 10. From 10 the stem *8'* the points *1* project toward the points of the opposite electrodes. The lower extension of the part *8* is set within the base, and has a screw *10* in its end, and a hole for 15 a circuit wire *4*. In providing for the distributor connections the electrodes *6*, Fig. 9, are made with heads *5* that screw into the threaded sockets as shown. A screw *b'* sets 20 down toward the head. At the junction of the head *5* and the screw *6*, elongated holes 25 *7* are provided through the base for the insertion of connecting wires, as at *3*, the elongation of the holes admitting of the adjustments of the electrode *5*. The base is 30 enclosed within a casing *t²*, which is removably held to the base by springs *v* in the casing 35 and notches in the base similarly to the showing in Fig. 7.

In Fig. 5 the face of the base is shown to be recessed the full length of the conical recesses to receive a mica or other transparent body, as shown in Figs. 1, 2, 3 and 11. An opaque body may be used instead of a transparent, and the closure may be fitted tight, so that the sparking at the electrodes may be 35 in practically an airtight space. In Figs. 4 40 and 7 a glass is shown as covering the recesses.

In Fig. 1, which is a plan of the top of the device shown in Figs. 2 and 3, the connecting 40 terminal of the electrode *1* is shown to be inserted through the back of the base, the point *1* coming in range of the top electrode. The top electrode is omitted from the figure for clearness of the other details.

45 In Fig. 11 is shown a modification of the shape of the base from the one shown in Fig. 2. Except for the circular outer contour the device is the same as that shown in Fig. 2. The shape of the recess in the unit base, 50 or the separation of the recesses in the multi-unit bases, are important only as affecting the strength of the base, depending upon the material of the base. A minimum amount of substance is cut away as will secure a 55 clear vision of the sparking at the electrodes;

and the less open space there is the less will be the chances for dust accumulations, and the chances for short circuits between the various parts. Otherwise, a single elongated recess can be made in the combinations. The 60 combination can be made up in any number of units, for two to ten cylinder engines, or any required size. The multi-unit indicator can, of course, be made up of any number of the unit devices; likewise, a multi-indicator can be made up by combining in one base 65 air gap arrangements differing from those herein shown, and it is not intended that in making this invention it shall be limited to the exact arrangements of the parts as herein shown. 70

In any vessel or vehicle the distance this indicator may be placed from the engine or distributor is unimportant, since the tension of the electric currents employed will render 75 negligible the resistance of the length of wire used for installation.

This device in the unit form affords a convenient means for testing the action of the spark plugs; and in the multi-units constitutes an indicator that will be a constant tell-tale upon the efficient working of an ignition system. In addition to that they are a means for overcoming weaknesses of insulation in spark plugs, acting upon the well 85 known principle of an auxiliary air gap.

Having described my invention, what I claim and desire to secure by Letters Patent, is—

1. In a spark indicator the combination 90 of an insulating body, a conical cavity in one end of the body, electrodes extending through said body and terminating in said cavity to form a spark gap, and means for making electrical connections to said electrodes. 95

2. In a spark indicator, the combination 100 of an insulating body, a conical cavity in one end of the body, electrodes extending through said body and terminating in said conical cavity to form a spark gap, a transparent inclosure of said conical cavity, and means for making electrical connections to said electrodes.

Signed at Peekskill, in the county of Westchester and State of New York, this 6th 105 day of August, A. D. 1915.

HOMER ANDERSON.
